R. WINSHIP

CHILD'S TABLE

Filed Aug. 5, 1922

UNITED STATES PATENT OFFICE.

ROSS WINSHIP, OF VALPARAISO, INDIANA.

CHILD'S TABLE.

Application filed August 5, 1922. Serial No. 579,898.

To all whom it may concern:

Be it known that I, ROSS WINSHIP, a citizen of the United States, residing at Valparaiso, in the county of Porter and State 5 of Indiana, have invented certain new and useful Improvements in Children's Tables, of which the following is a specification.

My invention relates to improvements in child's table and it more especially consists of the features hereinafter pointed out in the annexed claims.

The purpose of my invention is to provide a child's table that is simple in construction, quite rigid and yet easily adjustable for use so that the table top can be tilted through an angle of approximately 90 degrees or 45 degrees on each side of its central horizontal position; that provides clamping means for detachably holding the 20 table top so that if desired it can be turned over to thereby make both sides of the table top available for use; that provides means for adjusting the table top to different heights; that further provides spring pressed clamping 25 means to hold the table top in position between a pair of clamps; and that makes use of independently movable clamps which are automatically aligned by the table top, thus eliminating complicated and expensive 30 constructive features which would be required if the clamps were in rigid relation to each other.

With these and other objects in view, I illustrate in the accompanying drawing such 35 instances of adaptation as will disclose the broad underlying features without limiting myself to the specific details shown thereon and described herein.

Figure 1 is a front elevation of an assembled child's table.

Fig. 2 is an end elevation of Fig. 1.

Fig. 3 is a plan view of Fig. 1.

Fig. 4 is an elevation of one end of the table support showing means for securing 45 vertical adjustment for the table top.

Fig. 5 is a cross section of Fig. 4.

Fig. 6 is an enlarged detached elevation of the clamping portion of the table top, in modified form.

Fig. 7 is a view similar to Fig. 6 showing a spring pressed clamp.

Fig. 8 is a detached cross-section of a modified vertical adjustment.

Fig. 9 is a perspective of a wire formed 55 clamp.

In practically carrying out my invention, I may use any desired shape of supports 1 which take the place of ordinary table legs. These at the bottom end may have feet 19 formed thereon as shown in Fig. 2. 60 They are held together by a tie-piece or foot rest 2 which may be secured to the supports 1 by screws or by means of any detachable expedients, such as a mortise and tenon 26 cooperating with a holding 65 pin, as shown in Fig. 1, so as to make it easy to pack the table in small space for shipment.

The upper ends of the supports 1 are provided with a distance rod 4. This rod is 70 threaded at both ends where it passes through the supports. The upper ends of the supports are rounded at 18 so that in whatever angular position the table top may be placed its weight will still rest on 75 the support. This is clearly shown in Fig. 2. On the inside of each support at the upper end, clamping plates are placed. These plates comprise a depending portion 6 through which a hole is pierced for the 80 distance rod 4. The part 6 is joined to a lengthened horizontal portion 5 and this in turn is joined to a short vertical portion 7 which terminates in a short horizontal flange 8. The flange 8 enters slot 10 formed 85 in the side edges of the table top 3 as specially shown in Fig. 6. The table top 3 is removable from the clamps. It may be turned over so as to bring the underface 90 uppermost and the faces of the table top 90 may be finished in the same manner, or one or both may be finished so as to make the top available for use with chalk, crayons, etc.

The rod 4, as stated, passes through the depending portion 6 of the clamps and it 95 also passes through an opening formed in the supports 1 at the center of the rounded end 18. One or more lock nuts 12 on the inside of the clamping plates serve to define the lateral position of such plates on the rod 4 holding them lightly in position against the supports 1 while the part 5 of such plates rests on the rounded ends 18 of the supports 1, thus relieving the plates from any strain that might be placed upon them by the weight of the table top. Clamping wing-nuts 13 are threaded on to the ends of the rod 4 outside of the supports 1. By loosening these nuts the clamps with their attached table top may be shifted on 105 110

the rod 4 as an axis by means of the table top 3 and when the desired position is found the thumb nuts are clamped to hold the parts against further movements. If the table top is to be turned over, one of the clamps must be removed from its groove 10 when the top may be pulled endwise to free it from the other clamp, turned over and replaced. In order that the clamps will not injure the table top, felt cushions 9 may be secured to the clamps where they would otherwise directly engage the top.

Instead of the clamps being rigidly aligned in respect of each other, I mount them so as to be entirely free and have movement independent of each other and place entire dependence on the table top 3 with its slots 10 to align the clamps and secure their simultaneous movement as the table top is tilted. It is understood that I do not limit myself to any specific type of clamp because any practical alternative will fall within the spirit of my invention. The reason for this self aligning feature being practical will be seen by inspecting Fig. 3 wherein is shown that the dimension 11 representing one-half of the length of the clamp is positioned on each side of the center line of the table which coincides with the center of the rod 4.

In case it is desired to use a spring clamp the expedient illustrated in Fig. 7 may be used. This comprises a pivoted portion 27 that terminates in a rounded end 14 adapted to enter a corresponding groove 28 formed in the edge of the table top, which groove may extend the length of the clamping element or it may extend throughout the entire width of the top in which case the top may be slid out lengthwise of the grooves by simply loosening the pressure of one of the clamping elements 27. It may be found that a single spring pressed element 27 engaging one edge of the table top will be quite sufficient to hold the top in engagement with an ordinary form of clamp placed at its other edge. The spring pressed element 27 may be pivoted at 15 to the horizontal portion 5 of an ordinary clamping plate thereby becoming a substitute for the parts 7 and 8 shown in Fig. 6. A finger extension 16 is formed on the part of 27 below the pivot point 15 and a spring 17 is placed between this finger extension and the horizontal portion 9 of the clamp. This serves to hold the rounded edge 14 in the groove 28, and also serves to hold groove 10 of the table top 3 in engagement with flange 8 of the other clamping plate, or if a second spring pressed clamp is used its rounded edge 14 would engage the second groove 28. The groove 28 may be formed in all of the edges of a square table top so that if for any reason it is desired to shift the top so that what was its lower and upper edge will become its side edges. It is of course understood that the

table spring 17 may be made as stiff as is found necessary to properly hold the table top in place.

Whenever it is desired to make a child's table adjustable vertically, it may be done in a number of different ways. One such way is illustrated in Fig. 4 wherein a guide plate 24 is secured to each of the supports 1 on the inside of the upper end of the supports. Sliding members 20 grooved at 23 are rounded at their upper end similar to the arc 18 and a screw 21 passes through the part 20 and the depending portion 26 of a clamping plate. A clamping nut 22 is placed on the screw 21 so as to firmly hold the clamping plates and table top in any desired angular position within the clearance limits of my device. The members 20 are provided with lengthwise slots 25 through which the rod 4 passes. The desired vertical position of the table top is maintained by using the clamping nuts 13 found on each end of the rod 4. The members 20 are held against edgewise movement by flanges of the guide plates 24 entering grooves 23 formed in the edges of members 20. It is of course obvious that any one of numerous well known expedients may be used instead of the grooves 23 and guides 24 without departing from the broad spirit. An instance of another form is shown in Fig. 8 wherein the adjustable sliding members 29 each having two flanges 31 formed thereon adapted to slide in saw cut grooves 30 of the supports 1. The upper end of the members 29 are rounded similar to the upper ends of supports 1 or the members 20 to accomplish the same purpose. These members 29 also have a slot 37 similar to the slots 25 of the members 20 to provide for the passage of the distance rod 4. It is immaterial whether the distance rod 4 connects the upper ends of the supports 1 or joins the members 20 or 29. This alternative location of the rod 4 is shown in Fig. 4 wherein a dotted line extension of the bolt 21 suggests its substitution by rod 4.

There are also other modifications which may be made without departing from the spirit of my invention as instanced in Figs. 6 and 9. In the former the portion 6 of a clamping plate is placed outside of the supports 1, and the part 5 has a lateral extension 32 which rests on the upper end of the supports 1 performing a similar function to that of part 5 when the portion 6 is placed on the inside of supports 1 as shown in Fig. 1, or on members 20 as shown in Fig. 4. The part 7 of the clamping plate in Fig. 6 terminates in a flange 33 which will engage the upper face of the table top in a protected manner so as not to injure the same thus forming a substitute for the flange 8 shown in Figs. 1 and 4.

The clamping plates may be substituted

by bent-up-spring wire clamps 38 as shown in Fig. 9. These wire clamps have bent in ends 41 adapted to enter holes 40 formed in the edges of the table top. They have 5 horizontal portions 42 which serve the same purpose to support the top as the part 5 of the clamping plates. Each spring clamp 38 has an eye 39 formed about midway between its ends through which either bolts 10 21 or rod 4 may pass. These spring clamps may be detached from the table top without specially loosening the thumb nuts 13 or 22 by simply bending them outward so as to withdraw the ends 41 from the holes 40. 15 In Fig. 7 a pencil box or drawer holding expedient 36 is shown wherein a trough like portion 34 with bent up flanges 35 is secured to the part 6 of the clamping plate by riveting or otherwise to hold a pencil box 20 or drawer 36 which may be made slidable in the holder 34 if desired. Each of the clamping plates may be provided with the expedient shown in Fig. 7 so as to have separate receptacles along each edge of the table 25 top. Whenever the table top is tilted, the drawer or receptacle 36 will remain parallel with it so as to be easily accessible under all adjustments of the table. Even though the title "Child's table" has been used, I do not 30 limit myself to this specific adaptation.

From the description and drawing it will be seen that a child's table constructed in accordance with my invention will be very sturdy and efficient, meeting the various and 35 varying needs of child life, thus forming an instrument which will enable the parents to effectively direct the expanding possibilities of children and conserve their future development.

40 What I claim is:

1. In a tilting top table, a table top, a pair of standards thereunder, means for supporting the table top on the standards, cooperating means between the lower face 45 of the table top and the upper edge of the standards for limiting the angular position of the parts to each other, means for pivoting the parts to each other, and means for locking them in different positions.

50 2. In a child's table, a pair of suitable supports, means for holding them in related positions with respect to each other, a distance rod joining said supports near their upper ends, separate and independent 55 clamping plates movable on said rod while in engagement with the upper end of the supports, a table top having grooves in its edges removably held between such clamping plates, and means for detachably holding 60 the table top grooves in engagement with said clamping plates to thereby align the plates to each other and cause the same

to move together and with the top when it is adjusted.

3. In a child's table, a suitable support 65 comprising end members detachably secured to each other, a distance rod passing from one support to the other, an arc of a circle forming the termination of the upper ends of the supports whose center is the same as that of the rod, independent and separate clamping plates on said rod while resting on the rounded ends of the supports, and a removable table top attachably and detachably secured to said plates. 70 75

4. In a tilting top table, a removable table top, a pair of standards thereunder, means for pivotally securing the table top to the standards, and means comprising pivoting and holding plates placed between the lower 80 surface of the table top and the standards adapted to limit the angular position of the table top on the standards independently of the pivoting means.

5. In tilting tables, a table top, standards 85 beneath the same, pivoting plates between the table top and the standards, and means for limiting the angular position of the table top by the cooperating upper edges of the standards. 90

6. In adjustable tables, a removable and reversible table top, detachable clamping means therefor, suitable supports in pivoted relation to the clamping means, a drawer supporting extension from said clamping means, and means for holding the table top, drawer support, and clamping means in different angular positions while such parts retain their same relation to each other throughout the adjustment of the table top. 100 95

7. In table supports, a reversible table top having grooves in its edges a pair of supporting members constituting a substitute for two pairs of table legs, separate clamping means pivoted near the upper ends of said supports, means for holding said supports spaced apart in definite relation to each other, means for detachably holding said clamping means in said grooves, and means for variably positioning the clamping means on the supports to thereby tilt the table as desired. 105 110

8. In tilting top tables, a table top, standards thereunder, pivotal means on the standards, means for pivotally clamping the table top to the standards, and cooperating means between the table top and the edges of the standards for limiting the extreme angular service positions of the top independently of the pivotal means. 115 120

In testimony whereof I affix my signature.

ROSS WINSHIP.
